P. BERKEY

EGG CARTON

Filed Sept. 28, 1923

Trevenor:
Peter Berkey,
64 W. F. Freudenreich
Atley

UNITED STATES PATENT OFFICE.

PETER BERKEY, OF CHICAGO, ILLINOIS.

EGG CARTON.

Application filed September 28, 1923. Serial No. 665,292.

To all whom it may concern:

Be it known that I, PETER BERKEY, a citizen of the United States, residing at Chicago, county of Cook, State of Illinois, have 5 invented a certain new and useful Improvement in Egg Cartons, and declare the following to be a full, clear, and exact description of the same, such as will enable others skilled in the art to which it pertains to 10 make and use the same, reference being had to the accompanying drawing, which forms a part of this specification.

Cellular cartons for packaging small quantities of eggs are usually made of light 15 material, for the purpose of reducing their cost. The result is that the cartons are not very rigid, but yield more or less during the process of handling them. In the most common type of egg carton the cells are formed 20 by means of transverse partitions and a single longitudinal partition suitably interlocked with the latter; the longitudinal partition being made out of the same material as the remainder of the carton.

25 The object of the present invention is to stiffen and reinforce cartons of the kind described, without adding any considerable amount to the cost of the same and without requiring any alteration in the construction 30 of the main portion of the cartons. In carrying out my invention, I stiffen the longitudinal partition, thereby strengthening and reinforcing the entire carton. This is conveniently accomplished by making the partition member out of a blank of twice the 35 width or depth of the ordinary partition, and folding the blank along its longitudinal center line. This construction lends itself readily to the strengthening of the carton 40 in another way. Thus, in the common form of carton in which the body member and transverse partitions are made out of a single sheet, the transverse partitions being secured only at their upper corners to the 45 front and rear walls, there are no end walls, as such, but the two end partitions serve as end walls. Consequently, the effective end walls of a carton of this kind are fastened only at two corners and are not braced by 50 being attached at three edges to the bottom and front and rear walls. My improved

longitudinal partition may conveniently be made much longer than the length of the carton and have its ends fashioned into sections which may be bent laterally into engagement with the front and rear walls of the carton and thus form actual end walls for the carton. 55

Viewed in one of its aspects, my invention may therefore be said to have for its object to produce a simple and novel cellular carton in which the end walls are formed out of the same material as, or are connected to a detachable longitudinal partition. 60

The various features of novelty whereby 65 my invention is characterized will herein-after be pointed out with particularity in the claims; but for a full understanding of my invention and of its objects and advantages, reference may be had to the following 70 detailed description taken in connection with the accompanying drawing, wherein:

Figure 1 is a perspective view of a carton constructed in accordance with the present invention, the cover being raised, and a fragment of one of the endmost transverse partitions being broken away; and Fig. 2 is a plan view of the longitudinal partition in its flattened condition. 75

The carton illustrated is substantially 80 the same as that shown in my prior Patent No. 1,124,266, dated January 12, 1915 and, viewing my invention in certain of its aspects, the carton should take this form; however, certain of the features of my invention 85 are applicable to cartons otherwise constructed, as will be understood from the following description.

Referring to the drawing, 1, 2 and 3 represent respectively the front, back and bottom wall of a carton and 4 is the cover member of the same. 5 is a locking strip on the free long edge of the cover. The transverse partitions are indicated at 6, each being connected at its front upper corner, as 95 indicated at 7, to the upper edge of the front wall of the carton, and being similarly connected at its upper rear corners, as indicated at 8, to a strip 9 which is fastened to the back side of the carton. All of the 100 parts heretofore described are made out of a single piece so that when the transverse par-

titions are caused to lie in a common plane parallel with the bottom of the carton, the carton may be collapsed in a flat condition; whereas, when the carton is expanded, the transverse partitions may be swung into vertical positions, as shown in the drawing, and hold the carton expanded. Each transverse partition is provided with a deep vertical notch extending downwardly through the upper edge at the middle, for the reception of a longitudinal partition, which should be provided with similar notches extending upwardly through the bottom edge thereof.

In accordance with my invention I form the longitudinal partition out of a blank 11 having twice the width or depth of the desired partition, and I crease this blank along the longitudinal center, as indicated at 12. The notches are produced by cutting slots 13 and 14 in the blank; these slots extending transversely of and across the crease and being spaced apart from each other to conform to the spacing of the transverse partitions. It will be seen that when the blank is folded along the line of the crease, the slots are transformed into notches which open out through the folded edge of the blank, so that the partition may be inserted in the carton in the same way as an ordinary longitudinal partition. However, since the longitudinal partition is of double thickness, it serves as a backbone or stiffening piece for the entire carton.

Where it is desired that the longitudinal partition is to be applied to a carton of the style illustrated, and it is desired to form end walls on the carton, the blank out of which the partition is made is provided with end extensions, as shown. There is an extension at each end of the blank, these extensions being divided by being slit along lines 15 that are continuations of the line of the crease 12; the width of the extensions being equal to twice the height that the end walls should have, and their lengths being somewhat greater than one half the length of an end wall. The ends of the partition proper are defined by transverse creases 16, and other creases 17, parallel with and spaced apart from the creases 16 a distance equal to one half the width of the carton, divide each extension into end wall sections and locking flaps; there being at each end of the blank two end sections 18, each provided with a flap 19.

In assembling this partition in the carton, the partition is first folded along the longitudinal center, the end sections are bent laterally in opposite directions, and the flaps 19 are then bent inwardly at right angles to the end sections. The flaps pass between the vertical edges of the two endmost transverse partitions and the front and rear walls of the carton, each pair of end sections co-

operating to form a substantially continuous end wall resting at its lower edge on the bottom of the carton and having what may be termed flanged sides which engage with the inner faces of the front and rear walls and are pressed against the latter by the corresponding transverse partitions.

It will thus be seen that I have produced a simple means for stiffening egg cartons of any type having detachable longitudinal partitions and, furthermore, for forming comparatively strong, stiff end walls for such cartons as have heretofore had no actual end walls: without necessitating any change in the construction of the main portions or bodies of the cartons, by simply changing the form of the detachable longitudinal partition.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. A carton having a bottom wall and front and rear walls, transverse partitions extending between the front and rear walls, a removable longitudinal partition extending throughout the length of the carton and suitably interlocked with the transverse partitions, said longitudinal partition having at its ends sections forming end walls for the carton.

2. A carton having a bottom wall and front and rear walls, transverse partitions extending between the front and rear walls, a longitudinal partition extending throughout the length of the carton and suitably interlocked with the transverse partitions, said longitudinal partition having at its ends sections forming end walls for the carton, each of said end sections having a flap engaged with and lying parallel to the corresponding front or rear wall of the carton.

3. A carton having a bottom wall and front and rear walls, transverse partitions attached only at their upper corners to the front and rear walls, a longitudinal partition suitably interlocked with the transverse partition, said longitudinal partition having at the ends laterally-extending sections forming end walls for the carton, each of said sections having a flap engaged with one of the front or rear walls and lying between the same and an edge of one of the transverse partitions.

4. A longitudinal partition member for egg cartons comprising a blank creased along the longitudinal center throughout the middle portion and slitted at the ends along

lines forming continuations of said crease; said blank having slots cut into the same transversely of and across the crease, and transversely of and across the crease.

5. A longitudinal partition member for egg cartons comprising a blank creased along the longitudinal center throughout the middle portion and slitted at the ends along lines forming continuations of said crease;

said blank having slots cut into the same transversely of and across the crease, and 10 there being a crease extending transversely of each slitted portion of the blank near the outer end of such slitted portion.

In testimony whereof, I sign this specification.

PETER BERKEY.
